UNITED STATES PATENT OFFICE.

ALBERT J. B. HARRIS AND RAYMOND S. HUMBURCH, OF ROCHESTER, NEW YORK.

DOOR LOCKING AND OPERATING MECHANISM.

1,232,302.

Specification of Letters Patent.

Patented July 3, 1917.

Application filed July 6, 1915. Serial No. 38,112.

To all whom it may concern:

Be it known that we, ALBERT J. B. HARRIS and RAYMOND S. HUMBURCH, citizens of the United States, residing at Rochester, in 5 the county of Monroe and State of New York, have invented a certain new and useful Improvement in Door Locking and Operating Mechanism, of which the following is a full, clear, concise, and exact description, reference being had to the accompanying drawings, forming a part of this specification.

This invention relates to improvements in door locking and operating mechanism.

15 An object of the invention is to provide simple and efficient means for securely closing and positively opening a slidable door, in combination with improved means for sealing the door operating mechanism.

20 Another object of the invention is to provide a door closing and opening mechanism, more particularly adapted for box car doors; said mechanism including a pivoted lever mounted on the door, and which 25 operates with a keeper secured to a door post, the keeper and lever having co-operating camming surfaces so arranged that in swinging the lever in one direction the door will be moved to fully closed position, and 30 when the lever is turned in the opposite direction the door will be positively forced open.

In the drawing forming a part of the specification, Figure 1 is a side elevation of 35 a portion of a box car, showing our improvement in connection therewith. Fig. 2 is a side elevation upon an enlarged scale, showing more particularly the door operating mechanism and sealing arrangement, the 40 dotted lines indicating the position of the lever in vertical position. Fig. 3 is a horizontal sectional view, taken on the line 3—3 of Fig. 2. Fig. 4 is a detail sectional view, taken on the line 4—4 of Fig. 2, and Fig. 5 45 is a vertical sectional view upon an enlarged scale, taken on the line 5—5 of Fig. 2.

In said drawing, 10 denotes the car having door post 11, and a sheet steel slidable door 12, mounted on suitable track 13. On 50 the outside of the post 11 is secured a substantially Z shape strip 14, adapted to form a stop and weather protector for the edge of the door. The door 12 is provided with a channel shaped strip 15 on its outer side 55 near the front edge thereof, and to the latter are riveted two L shaped castings 16 and 17,

the former being on the interior and the latter on the exterior, said castings 16—17 bracing the strip 15 in order to form a suitable support for the pivoted lever about to be described.

The improved operating mechanism, as shown, consists of a lever 18, pivoted as at 19, to the castings 16 and 17 on the door; and a keeper 20 secured to the door post. 65 The keeper 20 is in the form of a cast bracket having an offset double faced cam 21. The cam 21 has its upper face or camming surface 22 arranged eccentrically to the pivot 19 of the lever 18. The lever 18 70 is provided with a hook shaped portion 23, having a curved camming surface 24, arranged preferably concentrically with the pivot pin 19, and which is adapted to co-operate with the camming surface 22. The 75 lever 18 is also provided with another camming surface 25, which is arranged eccentrically to the pivot 19, and is adapted to co-operate with the under camming surface 26 of the member 21, as hereinafter described. 80 The lever 18 has pivotally connected therewith, a handle 27, it being observed that the axis of the pivotal connection between the lever 18 and the handle 27 extends at right angles to the axis of the pivot 19, whereby 85 the handle 27 may be swung toward and from the door 12.

The operation in closing and opening the door is, as follows:

Assuming the door to have been moved 90 substantially to closed position, and the lever and handle in the position indicated by dotted lines in Fig. 2, the lever and handle are then swung counter-clockwise, so that the camming surface 24 of the lever engages 95 the eccentrically arranged camming surface 22 of the keeper. As will be understood, this will pull the door tight against the stop, and the arrangement is such that if the lever 18 and handle 27 are held in horizontal position, this condition will be maintained. To open the door the lever and handle are swung downwardly or clockwise, whereupon the camming surface 25 will engage the camming surface 26 of the keeper 100 105 and positively force the door part way open.

To hold the lever and handle in proper position when the door is closed, we have provided an improved sealing arrangement, designated generally by the reference B. As 110 shown, this consists of a casting 28, riveted to the door, and having an outwardly ex-

tending slotted staple 29. Pivotedly mounted on the staple casting 28, is a lock member 30, having a hook shaped lower portion 31, adapted to swing over the staple 29, and provided also with a locking face 32, adapted to seat in a correspondingly arranged recess in the staple 29. Preferably, the pivotal connection for the lock member 30 is arranged, as indicated at 33 in Fig. 5, and coincides with one of the rivets for securing the casting 28, it being understood that a suitable bushing and spacing arrangement is provided to prevent binding of the member 30. The hook shaped section 31 of the lock 30 is provided with alined perforations, in which is adapted to be received, a seal pin 34, having an elongated slot 35, to permit the seal pin to slide up and down on the headed rivet 36, secured to the top of the lock member 30. The handle 27, as clearly shown in Figs. 2 and 3, is provided with a slot 37, to thereby permit the handle to be swung over the staple 29.

The sealing arrangement is shown in the drawing in the condition it would be when the door is closed and the car sealed. To release the handle 27, the sealing wire (not shown) which is adapted to be passed through the slot 38 in the lower end of the pin 34 is first removed, then the pin 34 is lifted so as to withdraw from the staple 29, then the lock member 30 is swung about its pivot 33, whereupon the handle 27 may be swung outwardly, as indicated in dotted lines in Fig. 3.

Although we have herein shown and described what we now consider the preferred embodiment of our invention, the same is merely illustrative, and we contemplate all changes and modifications as come within the scope of the claims appended hereto.

We claim:

1. The combination with a member having a door opening, and a slidably mounted door for closing said opening, of a keeper mounted on said member having fixed opening and closing camming surfaces, a lever mounted on said door and pivoted about an axis perpendicular to the face of the door, said lever having a hook shaped end on one side of its pivot, said end being provided

with two opposed camming surfaces arranged to coöperate with said camming surfaces on the keeper, said lever having also a handle on the opposite side of said pivot, and means for locking and sealing said handle.

2. The combination with a member having a door opening, and a slidably mounted door for closing said opening, of a keeper mounted on said member having opening and closing camming surfaces, a lever pivoted to said door near its front edge, said lever having a hook shaped end provided with camming surfaces coöperable with said camming surfaces of the keeper, said lever being oscillatable in a plane parallel to the face of the door, said lever having also an operating handle pivotally connected thereto, a staple secured to the door, said handle being slotted to thereby permit it to be positioned over the staple, a lock pivotally mounted on said door and adapted to swing in a plane parallel to the face of the door, and a seal pin slidably mounted on said lock and adapted to extend through said staple and secure said handle in locked position.

3. In mechanism of the character described, the combination with a member having a door opening and a slideable door for closing said opening, of a keeper mounted on said member, a lever pivotally mounted on said door, said lever being provided with a slotted operating handle, a casting secured to said door, said casting having a staple over which said slotted handle is adapted to be positioned, a lock pivotally mounted on said casting and adapted to swing in a plane parallel to the face of the door, said lock having a portion adapted to fit over the outer end of said staple, and a seal pin slidably mounted on said lock by means of a pin and slot arrangement.

In witness that we claim the foregoing we have hereunto subscribed our names this 8th day of June, 1915.

ALBERT J. B. HARRIS.
RAYMOND S. HUMBURCK.
